US0D1070862S

(12) **United States Design Patent** (10) Patent No.: **US D1,070,862 S**
(45) Date of Patent: ** Apr. 15, 2025

(54) **INDICATOR LIGHT OF LAPTOP COMPUTER**

(71) Applicant: **ASUSTEK COMPUTER INC.**, Taipei (TW)

(72) Inventors: **Fu-Yu Cai**, Taipei (TW); **Chun-Fu Chen**, Taipei (TW); **Che-Hsiung Chao**, Taipei (TW); **Ming-Chih Huang**, Taipei (TW); **Tong-Shen Hsiung**, Taipei (TW); **Shang-Chih Liang**, Taipei (TW)

(73) Assignee: **ASUSTEK COMPUTER INC.**, Taipei (TW)

(**) Term: **15 Years**

(21) Appl. No.: **29/824,822**

(22) Filed: **Jan. 27, 2022**

(51) LOC (15) Cl. **14-02**

(52) U.S. Cl.

(57) **CLAIM**

The ornamental design for an indicator light of laptop computer as shown and described.

DESCRIPTION

FIG. 1 is a front perspective view of an indicator light of a laptop computer showing our new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top plan view thereof;

FIG. 7 is a bottom plan view thereof; and,

FIG. 8 is an enlarged partial view of portion 8 in FIG. 1.

The dotted broken lines illustrate portions of the indicator light of a laptop computer which form no part of the claimed design. The dashed broken lines illustrate the boundaries of the enlarged view in FIGS. 1 and 8 and form no part of the claimed design.

1 Claim, 8 Drawing Sheets
